UNITED STATES PATENT OFFICE.

GEORGE R. STEWARD, OF LONDON, ENGLAND, ASSIGNOR OF TWO-THIRDS
TO EDWIN EAGLING GLASKIN, OF SAME PLACE, AND JOSEPH CASH, OF
COVENTRY, ENGLAND.

FURNACE-DOOR.

SPECIFICATION forming part of Letters Patent No. 604,093, dated May 17, 1898.

Application filed June 24, 1897. Serial No. 642,076. (No model.)

To all whom it may concern:

Be it known that I, GEORGE RICHARD STEWARD, of 15 Queen street, in the city of London, England, have invented certain new and useful Improvements in the Construction of Furnace-Doors, of which the following is a specification.

The object of this invention is to produce, as far as possible, a smokeless furnace, attempting to secure which have been frequently made and with varying results. To attain this object, I introduce, through the furnace-door, air in such a manner that it becomes heated before it commingles with the smoke and gases distilled from the incandescent fuel of the furnace, and such commingling is effected so as to insure a more complete combustion than heretofore of the smoke and gases evolved.

I am aware that many inventions have admitted air to the furnace through the fire-door and that the air so admitted has been deflected in various ways; but the means which I employ for insuring the heating and commingling of the air with the gases of combustion is of such a character as will cause it to produce whirling streams of heated air that will act more or less independently of each other when first meeting with the gases of combustion, and thereby insure a more perfect commingling of the admitted air with the generated vapors of the furnace than has heretofore been effected.

In the accompanying drawings, Figure 1 shows in elevation the inner face of the furnace-door fitted according to my invention. Fig. 2 is a sectional plan view taken in the line 1 2 of Fig. 1, and Fig. 3 is a vertical section taken in the line 3 4 of Fig. 1 in the direction of the arrow.

The furnace-door A is formed with longitudinal vertical openings $a a^*$. (Shown in dots at Fig. 1 and more clearly in the section Fig. 2.) These openings are covered by a metal box B on the front of the door, having openings in its front and in all its sides to leave free ingress for the air, which will absorb heat from contact with the metal of the door before entering the furnace through the openings $a a^*$. Of these openings there are

two pairs, and each opening is covered with a hollow metallic projection or air-trunk, (marked, respectively, $b b^*$), which severally form a curved air-passage about equal in breadth to the length of the opening which it covers. These curved air-passages are arranged in pairs with the curves turned inward, so that the vents of each pair of curved passages are opposed to each other, but in different planes. The form of these projections or trunks will consequently be such that the curved passages $b^* b^*$ will have a radius greater than the curved passages $b b$. The object of this arrangement is to deliver into the furnace currents of air from the passages $b^* b^*$, that will "overlap" (so to speak) the currents of air issuing from the passages $b b$. By thus admitting streams of air through the fire-door which are heated, as before explained, I effect the desired commingling of the air with the gases of combustion, the air thus admitted by its whirling action effectually sucking up, as into a vortex, the ascending gases on their passage to the furnace-bridge.

The fire-door may have other openings for the admission of air below the curved guides, as shown at $c c$. These openings I cover by deflectors $c' c'$, set at different angles to the door-face, as shown at Fig. 3, the action of which is to cause the two streams of air admitted to impinge the one upon the other and direct a whirling stream toward the dead-plate, which deflects it toward the fire without interfering with the whirling action set up in the main supply.

Figs. 4 and 5 illustrate a modification of the means which I employ for producing the whirling effect above mentioned. Fig. 4 is a view of the inner face of the door; and Fig. 5, a vertical section of the same, taken on the line 5 6 of Fig. 4. In this case the openings in the door covered by the hollow metallic projections forming the curved passages are horizontal in place of vertical openings. There is but one pair of hollow curved projections $b b^*$, and they are situate over the middle of the door and extend nearly from side to side thereof. In this modification the like provision is made for causing the streams

of air which pass out from the curved passages to overlap the one the other as they enter the furnace, and thus produce the whirling action that is found necessary to effect 5 the intimate mingling of the air with the gases evolved from the fuel. Openings *c c*, provided with deflectors *c'*, are made in this door, as in that shown at Fig. 1, for the purpose of setting up a whirling action in the air admitted to the lower part of the fire-chamber.

What I claim is—

1. The combination with a furnace-door, having a pair or pairs of slits or openings, of curved air-trunks projecting into the furnace, 15 and forming air-passages, the vents of each pair of which are opposed to each other, but situate in different planes, as and for the purpose set forth.
2. The combination with a furnace-door 20 having slits or openings covered by curved air-trunks projecting inward, and arranged in pairs, with vents opposed to each other, but in different planes, of a metal box on the front of the door covering the slits, and having openings in its front, and in all its sides, 25 as and for the purpose set forth.
3. The combination with a furnace-door having slits or openings covered by curved

air-trunks arranged in pairs, with vents opposed to each other, but in different planes, 30 and a perforated metal box on the front of the door, covering the slits of other openings for the admission of air below the curved trunks and metal box, and having deflectors set at different angles to the door-face, as and 35 for the purpose set forth.

4. The combination, in a furnace-door, of slits or openings covered by curved air-trunks arranged in pairs with vents opposed to each other, but in different planes, of other air- 40 openings, below the curved trunks, and covered by deflectors set at different angles to the door-face, as and for the purpose set forth.

5. The combination with the dead-plate of a furnace, of a furnace-door having longitudinal openings near its lower edge each provided at its upper side with a deflector, said deflectors being set at different angles to the door-face, whereby a whirling stream of air is directed toward the dead-plate, and, by it, 45 deflected toward the fire, as set forth.

London, England, May 31, 1897.

GEORGE R. STEWARD.
